United States Patent Office.

WILLIAM SPRAGUE, OF LYNN, MASSACHUSETTS.

Letters Patent No. 78,148, dated May 19, 1868.

IMPROVEMENT IN WATER-CLOSETS.

The Schedule referred to in these Letters Patent and making part of the same.

TO ALL WHOM IT MAY CONCERN:

Be it known that I, WILLIAM SPRAGUE, of Lynn, in the county of Essex, and State of Massachusetts, have invented a new and improved Water-Closet; and I do hereby declare that the following is a full, clear, and exact description thereof, which will enable others skilled in the art to make and use the same, reference being had to the accompanying drawings, forming part of this specification.

This invention relates to a new and improved method of constructing water-closets, whereby the same are rendered more simple in their construction, and the escape of offensive gases from them is prevented. In the accompanying plate of drawings—

Figure 1 represents a central vertical section of my invention, taken in the line $z z$, fig. 2.

Figure 2 represents a central vertical section of the same, taken in the line $y y$, fig. 1.

Similar letters of reference indicate corresponding parts.

A is a box or casing, in which the cover and the mechanism for operating the same are contained; B is the movable seat, secured to the casing A by the hinges d ; C is the opening in the seat B; D is the concave cover; E is the lever, having upon the same the projection a^2 , and turns upon the pivot e' ; a^1 is a rock-shaft, to which the concave cover is attached, having upon one end of said rock-shaft the crank, a ; e is a connecting-link, connecting the crank, a , to the lever E; G is a spring, held in position by a screw, f ; h is a casing, to protect the lever E and the spring G.

The casing A is made in the same general form as the casings of water-closets now commonly in use, and is connected with any vault or sewer in the ordinary way.

Upon the top and front side of the casing A is hinged a seat, B. The seat B is of the ordinary form of seats for such purposes, and is provided with an opening, C, through the same. The cover D is a concave metallic disk, of greater diameter than the diameter of the opening C, and is secured by a suitable arm to an iron rock-shaft, a^1 , near the middle of the same. The object of the cover D being made concave, is, that the same may fit more tightly against the seat B under the opening C, and thus more effectually prevent the escape of gases through said opening C.

The rock-shaft a^1 rocks in suitable bearings upon the under side of the casing A, at one side of the seat B, and extends from the front to the rear of the same, at right angles to front of said casing, and is provided upon the back end of the same with a suitable crank, a , keyed thereto in the ordinary way, in a line parallel with the arm to which the concave cover D is attached. The seat B is supported at the back edge of the same by an upward projection, a^2 , upon the lever E. The lever E is made of wood or other suitable material, and is pivoted within the casing A at one end, to the back of said casing A, on the side of the same opposite to the rock-shaft a^1 , as shown in the drawing, fig. 1. The lever E is supported at the other end in nearly a horizontal position, by a metallic spring, G, properly secured to and within the casing A under the lever E, by the screw f , as shown.

The lever E is connected with the crank a^1 , by a metallic connecting-link, e , as shown, so that the force of the spring G will hold the concave cover D firmly against the under side of the seat B, at the same time supporting the seat B by means of the projection a^2 , and in such way as that by any pressure upon the seat B, as the weight of any occupant of the same, the lever E will be forced down, and the concave cover connected thereto, as above shown, will be carried downwards and sidewise, and so to be entirely out of the way.

In the casing A is a pipe, F, made of wood or tin, or other suitable material of sufficient size to carry off any gases which may arise, and would otherwise be contained in said casing, said pipe F opening at the other end into any flue or chimney.

I claim as new, and desire to secure by Letters Patent—

In combination with the casing A, having outlet F and hinged seat B, the concave cover D, rock-shaft a^1 , link e , pivoted lever E, having extension a^2 , and spring G, all constructed and arranged to operate in the manner and for the purpose substantially as herein shown and described.

WILLIAM SPRAGUE.
